UNITED STATES PATENT OFFICE.

HENRY B. NORTHRUP, OF BEVERLY, MASSACHUSETTS.

ARCH SUPPORT FOR SHOES.

Application filed January 16, 1922. Serial No. 529,544.

To all whom it may concern:

Be it known that I, HENRY B. NORTHRUP, a citizen of the United States, residing at Beverly, in the county of Essex and State of Massachusetts, have invented new and useful Improvements in Arch Supports for Shoes, of which the following is a specification.

This invention is embodied in certain improvements in an arch support adapted to be loosely inserted in a shoe.

One object of the invention is to provide an arch support, the bearing surfaces of which may be conveniently modified in shape by a chiropodist to adapt the support to individual peculiarities or differences.

Another object is to enable the support to be made resilient, or of increased resilience by the application of a reinforcing spring member thereto.

Of the accompanying drawings forming a part of this specification,—

Figure 1 is a top plan view of an arch support embodying the invention.

Figure 2 is a section on line 2—2 of Figure 1.

Figure 3 is a bottom plan view.

Figure 4 is a section on line 4—4 of Figure 1, showing an interposed pad.

Figure 5 is a view similar to Figure 4, showing a differently arranged pad.

Figure 6 is a view similar to a portion of Figure 2, showing another pad arrangement.

Figure 7 is a perspective view of the reinforcing spring member.

Figure 8 is a section on line 8—8 of Figure 3.

In the drawings, 12 represents the body or sole member of the arch support, the same being preferably a piece of sole leather having a heel portion 12^a, and an anterior end portion 12^b. One edge of the member is curved upwardly at 12^c, as usual, to conform to a shoe upper above the inner edge of the shank portion of the insole, and to the corresponding portion of the foot, the form of the member being such that when loosely inserted in a shoe, it is confined in a predetermined position by internal surface portions of the shoe.

13 represents a clamping member of sheet material, preferably sheet metal, having heel end and anterior end portions conforming approximately to the heel and anterior end portions of the sole member. The clamping member is rigidly secured to the sole mem-

ber at a point near its heel end portion, by fastening means, preferably embodied in two rivets 14, engaged with the clamping member within the margin of its heel end portion, and arranged in tandem order lengthwise of the support, this arrangement of the rivets preventing the members 13 and 14 from swinging relatively to each other. The clamping member is placed under the sole member, and is free, excepting around the rivets, to move toward and from the sole member, so that a pad or cushion 16 may be inserted between any part of the margin of the clamping member and the corresponding part of the under surface of the sole member.

Figures 4, 5 and 6 show different forms of interposed pads. Figure 6 shows a pad interposed between the end portions of the members, in position to support the anterior end portion 12^b. Figure 4 shows a pad in position to support the upturned portion 12^c. Figure 5 shows a pad in position to support a portion of the sole member opposite the said upturned portion. A pad may be inserted between the members in position to support a part of the heel end portion 12^a of the sole member.

The upper side of the clamping member 13 is roughened to engage an inserted pad and prevent displacement thereof. Said member is preferably roughened by punching holes 18 therein in such manner as to form burrs 19 projecting from the upper surface of the clamping member, and adapted to indent a pad 16. When the support is in use, the pressure of the foot on the sole member causes the clamping member, which rests on the insole, to closely confine a pad inserted at any desired point between the members.

It will be seen that a chiropodist may fit the protector with a pad located and formed to provide a special support for any part of the foot requiring such support.

20 represents a reinforcing spring member, preferably of tempered steel, formed to be inserted between the sole member 12 and the free major portion of the clamping member 13, to impart resilience to the support. The spring member has an open longitudinal slot 21 at its heel end, so that said end is forked, and is adapted to bestride the rivets 14, as indicated by Figures 3 and 8, the longitudinal arrangement of the slot and the rivets preventing the spring member from

swinging edgewise relatively to the members 12 and 13. The forward end of the spring member may have a flexible tongue 22, adapted to loosely enter a slot 23 in the 5 clamping member, and prevent forward end-wise displacement of the spring member, when the support is in use. The fore portion of the sole member bears on the spring member and holds the latter against the 10 clamping member. When the support is removed from the shoe, the spring member may be readily applied and removed.

The area of the sole member 12 is considerably greater than that of the clamping 15 member, and the arrangement is such that the entire margin of the clamping member is spaced inwardly from the margin of the sole member, so that the sole member may be trimmed to reduce its area, and fit it to 20 peculiarities of a shoe. One side of the sole member may be marked to guide the operator in trimming.

The reinforcing member may be formed to project from one edge of the clamping 25 member 13, the projecting portion being curved to conform to the curvature of the sole member 12 at 12°, and rendered flexible by slits 25. The sole member 12 may be provided with pivoted buttons 26, adapted to 30 engage the forward end of the clamping member 13, and releasably confine said end.

I claim:

1. An arch support comprising a flexible sole member shaped to conform to portions 35 of the interior of a shoe, and the corresponding portions of the foot, and a flexible clamping member of sheet material under the sole member, fastening means rigidly connecting the heel end portions of the said 40 members within their margins, all portions of the margin and the major portion of the

fore part of the clamping member being free to move toward and from the sole member, so that a pad or cushion may be interposed 45 between various parts of the margin of said members, the upper surface of the clamping member being roughened to engage and prevent displacement of an interposed pad.

2. An arch support substantially as specified by claim 1, the said clamping member 50 being roughened by upwardly projecting burrs integral with said member and adapted to indent an interposed pad.

3. An arch support, comprising a flexible sole member shaped to conform to portions 55 of the interior of a shoe, and the corresponding portions of the foot, a flexible clamping member of sheet material under the sole member, a plurality of rivets rigidly connecting the heel end portions of the said 60 members within their margins, and arranged in tandem order lengthwise of the support, all portions of the margin and the major portion of the forepart of the clamping 65 member being free to move toward and from the sole member, and a reinforcing spring member formed to be interposed between the sole and clamping members, and provided in its heel end with a longitudinal slot adapted to bestride said rivets, when the spring 70 member is moved rearwardly between the sole and clamping members, the arrangement of the said rivets and slot being such that the sole and clamping members are prevented 75 from swinging relatively to each other, and the spring member is prevented from swinging relatively to the sole and clamping members.

In testimony whereof I have affixed my signature.

HENRY B. NORTHROP.
